DEVICE FOR DRYING AND PRESERVING
RAZOR BLADES

Basil G. Eaves, Maplewood, N. J.

Application November 5, 1936, Serial No. 109,306

3 Claims. (Cl. 206—46)

The protection of safety razor blades to prevent them from rusting and to preserve the sharpness of the cutting edges thereof presents quite a problem to the users of safety razors, as 5 residual moisture quickly rusts the blade and destroys the keenness of the cutting edge; also, attempts to dry a blade after using the same tends frequently to distort the cutting edge, rendering the blade of short life.

10 In addition to the tendency of the cutting edge of a blade to become distorted when the blade is wiped subsequent to use, residual moisture is likely to be left which will produce a rapid corrosion of the blade. Furthermore, it frequently 15 happens that a blade will be left after use in a location which is favorable to the production of rust as well as rendering likely the loss of the blade or misplacement thereof.

15 In accordance with the present invention, there 20 is provided a small and handy device for maintaining a razor blade in usable condition while avoiding tendency of the blade to become rusted and distorted after use.

Furthermore, it has been found that by rotating 25 the use of safety razor blades, a more satisfactory shaving operation is obtained than if the same blade is used a number of consecutive times. For example, a different blade is used for each 30 day of the week. This resting of the blades, according to the theory, enables the molecules of 35 the steel to readjust themselves and the cutting edge gradually to spring back into its original condition as when the blade was new. However, it is known from experience and experiments 40 that the "resting" of razor blades apparently has a marked effect upon the cutting edges thereof.

One of the objects of the present invention is 45 to provide a holding device for razor blades, especially blades of the double edge or well-known Gillette type whereby a plurality of the blades may be stored and protected between times of use and which will maintain the blades in dry condition and thoroughly protected 50 against distortion of the cutting edge, which is likely to occur during the usual wiping and drying operations of the blade.

A further object of the invention is to provide a container for razor blades of the above 55 type wherein the blades will become self-drying when inserted in the container, and maintained in dry condition, while being held against accidental displacement from the protecting device.

A further object of the invention is to provide a device for rapidly drying razor blades

which facilitates the preservation of the cutting edges of the same, and provides a means for assuring a regular rotation in sequence in the use of the blades, so that a different blade may be used each day, thus enabling blades to be 5 "rested" and rotated once a week.

A still further object is the provision of a simple device which can be used for quickly drying a safety razor blade after use, thus eliminating the necessity of drying the blade 10 by means of a towel, or the like, into which it is customarily pressed, and which has a tendency to injured the cutting edge of the blade.

Further objects and advantages of the present invention will become apparent as the description 15 proceeds and the features of novelty will be pointed out in particularity in the appended claims; and the invention accordingly comprises the features of construction, combination of 20 elements, and arrangement of parts, which will 25 be exemplified in the construction hereinafter set forth, and the scope of the application of which will be indicated in the claims.

The invention may comprise several different 30 forms, as will be evident from a consideration of 35 the drawings of the application, the holding and protecting device of the present invention comprising a plurality of strips of blotting paper, or other absorptive or bibulous paper or equivalent material, the strips being bound together between suitable backing elements to form a book 40 which is generally similar to the well-known books in which postage stamps are contained and sold, or which may conform to the general appearance of the well-known packets or books 45 for safety matches. In the present construction, the bibulous sheets replace the match carrier member, the sheets being bound at one end, and being readily separable to permit ready insertion and removal of a desired blade.

The book of the present invention, moreover, is distinguished from the well-known stamp books not only by the substitution of bibulous strips for the customary waxed paper used in the stamp books, but also by the provision of a recess between the contiguous strips of dry material, the recesses being located in the bound end of the book and which are adapted to receive an end tab with which double edged blades customarily are provided.

50 By inserting the tab into its respective recess, each blade is positively held against slipping from position between the leaves, while the blade lies flat against the drying means therefor in the book. The absorptive properties of the leaves of 55

the book quickly result in the blade becoming thoroughly dry, and the blades will be thoroughly protected from moisture when they are not in use.

The invention will be understood more readily by reference to the accompanying drawings, in which—

Fig. 1 is a perspective view of one form of a protecting book for the razor blades as constructed in accordance with the present invention, the view indicating how the blades are retained in position in the protective holder of this invention.

Fig. 2 also is a perspective view of the holding book of Fig. 1, the view showing the provision of guide lines or markings on adjacent leaves outlining the periphery of a blade, and indicating to a user where to place a blade so that an end tab thereof will slip readily into a securing recess.

Fig. 3 is a sectional elevation taken through the bound end of the book shown in Figs. 1 and 2, the view being taken on the line 3—3 of Fig. 2.

Fig. 4 is a perspective view of a modified form of device, the view illustrating a razor blade being inserted into, or removed from, the device.

Fig. 5 is a perspective view of the device of Fig. 4, showing the device in resting position.

Fig. 6 is a side elevational view of the device as illustrated in Fig. 5.

Fig. 7 is a sectional view taken on the line 7—7 of Fig. 6.

Fig. 8 is a perspective view of a modified form of the invention.

Fig. 9 is a perspective view of a further modified form of the device, the view showing the device in open position.

Fig. 10 is a perspective view of the device shown in Fig. 9, but illustrating the device in closed position.

Referring more particularly to the drawings, it will be apparent that, in all of its forms, the present invention comprises a small book which opens at one end for the insertion of razor blades between adjacent leaves of the book, these leaves being composed of moisture-absorbent or bibulous paper, or the like, any grade of the usual blotting paper which has sufficient body and stiffness, being found suitable, such strips being sufficiently flexible, however, to be readily separated without breaking the body of the strips, so as to permit the insertion and removal of a blade between adjacent strips or leaves.

Referring first, for the purposes of description, to Figs. 1 to 3 inclusive, it will be apparent that the book is made up of cover members 5 and 7, between which are clipped any desired number of strips 9 of water-absorptive material, such as, for example, blotting paper or the like. Any fastening means may be substituted for the clips, it being preferred, however, that whatever fastening instrumentalities may be used, they penetrate through the strips or leaves so as to prevent accidental displacement of the strips from their bound relation between the cover members.

These strips 9 form the leaves of the book, between which the razor blades 11 may be inserted.

The cover members and the leaves are bound together adjacent to one end thereof, as indicated at 13, any suitable fastening means being employed for this purpose.

The cover strips 5 and 7, which may or may not be of absorptive material, are bent into a hinge as indicated at 15 and 17, and the leaves 75 of the book are similarly provided with a hinge

fold or crease for enabling them to be readily opened.

Between adjacent leaves of the book, and between the cover members of the leaves adjacent thereto, there are formed, in a suitable manner, the recesses 19, in which the end tabs 21 of the blades may be inserted. These recesses, therefore, provide means for frictionally holding the blades in position in the book.

These recesses 19 are concealed beneath the hinged portion of the leaves of the book, and in order to indicate to a user where a blade may be placed for its end to be slipped into its recess, the outline of a blade may be indicated by the application of suitable guide markings 23 to the leaves of the book. These markings define the outline of a blade, and are applied to both sides of each leaf. By placing the blade between the leaves so that it coincides with the markings 23, a slight push is all that is necessary to insert the tab 21 into one of the recesses 19. The markings 23 therefore provide a convenient indication for the place of the blades for enabling the blades to be slipped into the holding recesses. It will be apparent also that when the book is closed, the blades will be brought into close engagement with the absorptive leaves of the book, so that the blades will be dried and cleaned without the necessity of wiping them on a cloth or the like, with consequent tendency of deterioration of the blades. The present holder avoids the necessity of wiping the blades by hand, and preserves the blades in dry condition and free from rust.

A modified form of construction is shown in Figs. 4 to 7 inclusive.

As in the precedingly described modification, the device comprises a plurality of sheets 9a of blotting paper, or the like, which possess, as previously described, a sufficiently hard surface to enable the blades to be inserted and removed readily therebetween.

The sheets are preferably secured together at one end by means of a staple, or the like, 25, thereby binding the sheets 9a together in a pad-like assembly. This staple 25 has a width approximately $\frac{1}{8}$ inch, which is greater than the reduced portion or tab 21 of a razor blade, which is $\frac{1}{2}$ inch wide, and less than the distance between the cutting edges 27 of the blade. Instead of a staple a pair of eyelets or other suitable means (not shown), properly spaced could be used. Attached to the lowermost sheet 9a of blotting paper, is a suitable clip 29, which has a tongue 31 extending over the uppermost sheet, thus providing convenient means for securing together the loose ends of the sheets 9a, to prevent accidental displacement of the blades.

In accordance with the invention, there may be provided, preferably, eight sheets of any suitable moisture-absorbing material, seven of the sheets bearing the names of the days of the week, so that the particular blade that has been used for a certain day is readily ascertainable. This provision may be used, obviously, also in connection with the modification of the device shown in Figs. 1 to 3 inclusive. Thus, for example, if the day is Monday, the blade resting upon the sheet 9a marked Monday is the one to be used.

In operation, a wet blade after it has been washed is inserted between the sheets of blotting paper, in a manner which will be apparent from the drawings, by raising the uppermost sheet or cover and inserting the reduced portion or shoulder 21 of the blade within the recesses 19, or between the prong portion 33 of the staple 25. The

portion 21 of the razor blade will thus be engaged frictionally by and between adjacent sheets 9, 9a of blotting paper, whereby its movement is limited.

5 In Figs. 4 to 7 inclusive, since the distance between the prongs 33 is less than the distance between the longitudinal cutting edges 21 of the blade 11, there is no danger of the cutting edges being impaired by engagement with prongs 33.

10 In Fig. 8 there is shown a modified form of the invention, in which a paper or other suitable cover 35, similar to the covers provided for book matches is used to enclose a plurality of sheets 9b of blotting paper or any other suitable moisture-absorbing material. The cover has a turned-up portion 37 through which the sheets of blotting paper are secured by means of a staple 19 which has a width less than the distance between the cutting edges of a blade. On each side of the 20 sheets of blotting paper, the turned up portion 37 may be secured to the cover 35 by means of staples 41, thereby providing a convenient pocket for the reception of the ends of the blotting papers.

25 In operation, the wet blades are inserted or removed from between the several sheets of blotting paper 9b as indicated above. The cover 35 is provided with a flap 43, which may have a reduced portion 45 which is adapted to be inserted between upturned portion 37 and the sheets of blotting paper 9b, thus making a compact package which may be conveniently carried in the pocket or in a traveling kit; or, the flap 43 may be provided simply with a straight edge 41, as indicated in Figs. 9 and 10 for insertion beneath the upturned portion 37, and the side staples 41 may be omitted, as shown in Figs. 9 and 10, by suitably reducing the width of the cover 35.

Otherwise, the form of the device illustrated 40 in Figs. 9 and 10 is like the modification of Fig. 8, and the operation thereof is the same.

The present invention may comprehend also the use of releasable fastening means for binding the sheets together, whereby individual sheets 45 may be removed as they become used, and replaced by fresh sheets, or by loose leaf "refills," while there may be retained, if desired, the original backing members which may be made of any desired material and finished in a desired style of dressing or design.

50 It will be understood from the above description that the invention is not limited, necessarily, to the specific details of the construction as are herein specifically illustrated and described, but 55 it will be apparent that such details are subject to various modifications which will become apparent to one readily skilled in the art, without departing from the spirit of the invention; and it will be understood, therefore, that it is intended 60 and desired to include within the scope of the invention such modifications and changes as may be necessary to adapt it to varying conditions and uses. It is also to be understood that the following claims are intended to cover all of the 65 generic and specific features of the invention

herein described, and all statements of the scope of the invention which, as a matter of language, might be said to fall therebetween.

What is claimed is:

1. In a protective package adapted to hold a plurality of razor blades comprising a book of larger dimension than said blades having a plurality of water-absorbing leaves therein, means for binding said leaves together adjacent to one end of the book while leaving the other end of the book open for removal or insertion of a razor blade between adjacent leaves, said binding means being transversely spaced to provide therebetween an unbound portion, the width of said portion being slightly greater than the width of one end of a razor blade, one end portion of each of said blades being insertable in said unbound portion between adjacent leaves, whereby said blades are held in position when said book is opened, said adjacent leaves closely engaging a blade when said book is closed thereby enabling said absorbent leaves to dry said blade. 5

2. In a protective package adapted to hold a plurality of razor blades comprising a book of larger dimension than said blades having a plurality of water-absorbing leaves therein, means for binding said leaves together adjacent to one end of the book while leaving the other end of the book open for removal or insertion of a razor blade between adjacent leaves, said binding means being transversely spaced to provide therebetween an unbound portion, the width of said portion being slightly greater than the width of one end of a razor blade, one end portion of each of said blades being insertable in said unbound portion 10 between adjacent leaves, whereby said blades are held in position when said book is opened, said adjacent leaves closely engaging a blade when said book is closed, thereby enabling said absorbent leaves to dry said blade. 15

3. In a protective package adapted to hold a plurality of razor blades comprising a book of larger dimension than said blades having a plurality of water-absorbing leaves therein, means for binding said leaves together adjacent to one end of the book while leaving the other end of the book open for removal or insertion of a razor blade between adjacent leaves, said binding means being transversely spaced to provide therebetween 20 an unbound portion, the width of said portion being slightly greater than the width of one end of a razor blade, one end portion of each of said blades being insertable in said unbound portion between adjacent leaves, whereby said blades are held in position when said book is opened, said adjacent leaves closely engaging a blade when said book is closed, thereby enabling said absorbent leaves to dry said blade. 25

4. In a protective package adapted to hold a plurality of razor blades comprising a book of larger dimension than said blades having a plurality of water-absorbing leaves therein, means for binding said leaves together adjacent to one end of the book while leaving the other end of the book open for removal or insertion of a razor blade between adjacent leaves, said binding means being transversely spaced to provide therebetween 30 an unbound portion, the width of said portion being slightly greater than the width of one end of a razor blade, one end portion of each of said blades being insertable in said unbound portion between adjacent leaves, whereby said blades are held in position when said book is opened, said adjacent leaves closely engaging a blade when said book is closed, thereby enabling said absorbent leaves to dry said blade, and a clip for holding the unbound end of said leaves together. 35

5. In a protective package adapted to hold a plurality of razor blades comprising a book of larger dimension than said blades having a plurality of water-absorbing leaves therein, means for binding said leaves together adjacent to one end of the book while leaving the other end of the book open for removal or insertion of a razor blade between adjacent leaves, said binding means being transversely spaced to provide therebetween 40 an unbound portion, the width of said portion being slightly greater than the width of one end of a razor blade, one end portion of each of said blades being insertable in said unbound portion between adjacent leaves, whereby said blades are held in position when said book is opened, said adjacent leaves closely engaging a blade when said book is closed, thereby enabling said absorbent leaves to dry said blade, and a clip for holding the unbound end of said leaves together. 45

6. In a protective package adapted to hold a plurality of razor blades comprising a book of larger dimension than said blades having a plurality of water-absorbing leaves therein, means for binding said leaves together adjacent to one end of the book while leaving the other end of the book open for removal or insertion of a razor blade between adjacent leaves, said binding means being transversely spaced to provide therebetween 50 an unbound portion, the width of said portion being slightly greater than the width of one end of a razor blade, one end portion of each of said blades being insertable in said unbound portion between adjacent leaves, whereby said blades are held in position when said book is opened, said adjacent leaves closely engaging a blade when said book is closed, thereby enabling said absorbent leaves to dry said blade, and a cover for said leaves having a portion folded over the bound end of said leaves, and a flap on said cover adapted to be bent over the open end of said leaves to maintain the flap in closed position. 55
